CLAIM

The ornamental design of a clothes dryer exhaust hose coupler, as shown and described.

DESCRIPTION

FIG. 1 is a perspective view of a clothes dryer exhaust hose coupler showing my new design broken away to indicate indeterminate length and partially cut away, it being understood that the fragmentary encircling line pattern represents ribbing and is repeated uniformly throughout the length of the exhaust hose section thereof;

FIG. 2 is an enlarged top plan view of a coupler shown separately for clarity of illustration thereof;

FIG. 3 is an enlarged bottom plan view of a coupler shown separately for clarity of illustration thereof;

FIG. 4 is an enlarged side view of a coupler shown separately without the clamp handle and draw band for clarity of illustration thereof; and,

FIG. 5 is an enlarged opposite side view of a coupler shown separately without the clamp handle and draw band for clarity of illustration thereof.

The broken line showing of the split band bushing is for illustrative purposes only and forms no part of the claimed design.
